[57] CLAIM

The ornamental design for a case for tape player and headphone, as shown and described.

DESCRIPTION

FIG. 1 is a perspective view of a first embodiment of a case for tape player and headphone showing my new design;

FIG. 2 is a top plan view of the first embodiment;

FIG. 3 is a left side elevational view thereof;

FIG. 4 is a front elevational view thereof;

FIG. 5 is a bottom plan view thereof;

FIG. 6 is a right side elevational view thereof; and

FIG. 7 is a rear elevational view thereof.

FIG. 8 is a perspective view of a second embodiment of a case for tape player and headphone showing my new design;

FIG. 9 is a top plan view of the second embodiment;

FIG. 10 is a left side elevational view thereof;

FIG. 11 is a front elevational view thereof;

FIG. 12 is a bottom plan view thereof;

FIG. 13 is a right side elevational view thereof;

FIG. 14 is a rear elevational view thereof;

FIG. 15 is a sectional elevational view thereof; taken along line 15—15 of FIG. 11; and,

FIG. 16 is a sectional elevational view thereof; taken along line 16—16 of FIG. 11.
